UNITED STATES PATENT OFFICE.

OTTO SCHLEMEYER, OF ELECTRA, TEXAS, ASSIGNOR OF ONE-HALF TO R. E. SCHEURER,
OF ELECTRA, TEXAS.

HYDRAULIC JACK.

Application filed May 27, 1926. Serial No. 111,954.

This invention relates to certain new and useful improvements in jacks and it refers more particularly to an improved hydraulic jack especially designed for heavy duty, such as in the oil field and similar industries, the primary object being to provide through the peculiar arrangement of elements, a stationary inner chamber and an outer housing movable by the action of fluid pressure.

10 The invention further contemplates the provision of a jack structure which is so constructed as to be readily dismantled for repair or other purposes, and in addition to its economical and practical assembly, an 15 added feature in the form of an auxiliary lift foot is made possible by the arrangement of the outer housing, of which the foot forms an integral part.

With these and other objects and advantages in view, the invention has particular reference to the salient features of construction and assembly of parts, which will be hereinafter more specifically described and illustrated in the accompanying drawings, 25 wherein:

Figure 1 represents a view of the invention in vertical elevation.

Figure 2 is likewise a view in vertical elevation of a jack constructed according to 30 the present invention.

Figure 3 is a detail view of the operating lever, and

Figure 4 is a view on lines 4—4 of Figure 2.

It is particularly pointed out in proceeding further, that while there are varied jack structures in which fluid pressure is employed as an operating medium, these such structures are usually dependent upon the 40 centermost element as an elevating member, while the outer housing and base remain stationary. In the construction of the present invention, the outer housing forms the lifting element, and in being so constructed, an added lifting surface, as previously referred to and hereinafter defined, is made 45 possible.

With the above in view, attention is directed to Figure 1 showing the invention in vertical elevation and in which a base member 1 is shown, having an upwardly extending cylinder 2, which latter is provided with an integral head portion 3, having a central, interiorly threaded aperture

therein. An annular chamber 4 is formed 55 within the cylinder 2 by mounting therein a central cylinder 5, which depends within the cylinder 2, to a point adjacent the bottom thereof. While the head portion 3 and the cylinder 2 is shown in the drawing as 60 being in one piece, it is of course apparent that these parts may be independent without affecting the efficient operation of the device.

Now, upon the lower end of the central 65 cylinder 5, a valve 6 is threaded or otherwise mounted, which in the present case is of the ball type. A piston 7 is adapted to reciprocate within the cylinder 5 above the valve 6 by the action of the piston rod 8 70 to which it is attached. A lever arm 9, as in Figure 2 is pivoted at its end to the upper end of the piston rod 8, and through this arm, reciprocal movement of the piston is effected, by manual or other actuation of the 75 hand lever 10, arranged to be detachably mounted upon the squared portion situated in an offset in the outer housing 12 of the pin 11 and upon which the other end of the lever arm 9 is pivotally mounted, as shown 80 in Figures 2 and 4.

Surrounding the bottom of the outer housing 12 is a collar 13, having a lifting surface 14 integral therewith as previously mentioned and illustrated in Figure 2 especially, while the roughened top surface 15 of the housing 12 may be more frequently used.

In operation the chamber 4 is first charged with fluid of comparatively heavy viscosity 90 and the jack assembled. Pumping of the piston 7 within the cylinder 5 will of course eject the fluid therefrom through the ports 16 in the head 6, up through the piston ports 17 on its down stroke, thence into the upper chamber 18 of the housing 12 to elevate the same. Packing 19, circumferentially surrounding the inner periphery of the outer housing 12 adjacent its bottom preventing 95 escape of fluid therefrom.

Now in order to lower the outer housing 12, the lever 20, protruding exteriorly of the cylinder 2, is depressed, which causes upward movement of the valve rod 21. In this manner the valve 22 is moved from its seat as shown, permitting the fluid to drain 105 back into its reservoir in the chamber 4.

It should be understood that while the in-

vention has been specially shown and described, certain changes as to shape, number of parts may be resorted to as fall within the meaning and scope of what is herein claimed.

I claim:

1. In a hydraulic jack, a base supporting a cylinder, a covering for said cylinder, a pipe entering said covering centrally thereof and depending within said cylinder to form an annular fluid reservoir; a plunger movable in said pipe to effect removal of fluid from said annular reservoir; an outer housing movable on said cylinder to receive the fluid removed from said annular chamber, means to effect movement of said plunger, and means to permit said fluid to be returned to said reservoir to lower the outer housing.
2. In a hydraulic jack, a base supporting a cylinder; a pipe depending within the cylinder to form an annular fluid reservoir; a movable piston within said pipe; a movable housing embodying said cylinder, and arranged to receive the fluid when pumped from said reservoir by the action of said piston, means to exteriorly actuate said piston, and means to return the fluid into said reservoir.
3. In a hydraulic jack, a fluid cylinder and reservoir supported upon a base and having a covering thereon; a pipe entering said covering and depending interiorly of said cylinder; a movable piston in said pipe having ports therein; a valve in the bottom of said pipe, an outer housing snugly surrounding said cylinder and arranged to receive fluid from said reservoir to elevate the same with respect to said cylinder; means for exteriorly actuating said piston, and means to drain the fluid from said housing to lower the latter.
4. In a hydraulic jack, a fluid cylinder and reservoir; a movable housing enclosing said cylinder and arranged to be elevated by the ingress of fluid from said reservoir; means for effecting such ingress, said means comprising a pipe depending into said reservoir having a piston therein; means for exteriorly actuating said piston, and means

for returning said fluid to the reservoir to lower the said housing.

5. A hydraulic jack including inner and outer cylindrical members, the latter of which members is provided with lifting surfaces adjacent its top and bottom and arranged to be movable; means for retaining fluid within said inner cylinder; means for forcibly transferring said fluid into said outer cylinder to cause the same to move upward and means for returning said fluid by gravity into said first cylinder to permit said outer cylinder to be lowered.

6. A hydraulic jack including inner and outer cylindrical members, the latter of which is movable vertically on said inner cylinder, and provided with lifting surfaces adjacent its top and bottom; means for retaining fluid in said first cylinder; means arranged to be actuated exteriorly of said outer cylinder to forcibly transfer fluid from the said first cylinder into said outer cylinder to elevate the same, and means to permit said fluid to be returned to said first cylinder to lower the outer cylinder.

7. An apparatus of the character described including an outer cylinder movable over a stationary inner cylinder; means for retaining fluid within said latter cylinder; a member depending within said latter cylinder having a valve and a movable piston therein; means for actuating said piston exteriorly of said outer cylinder to forcibly transfer said fluid to raise said outer cylinder and means exteriorly actuated to permit the fluid to return to said inner cylinder.

8. An apparatus of the character described having a stationary base and cylinder fluid reservoir; a cylinder movable outside of said latter cylinder having lifting surfaces adjacent its either end; means interiorly of said stationary cylinder arranged to be actuated exteriorly of said outer cylinder to pump fluid therefrom into said outer cylinder to elevate the same, and valve means to permit the fluid to drain back into said inner cylinder.

In testimony whereof I affix my signature.
OTTO SCHLEMEYER.
